(57) CLAIM

I claim the ornamental design for a shoe-exhibit, as shown.

DESCRIPTION

FIG. 1 is a perspective view, from one side, of a shoe-exhibit showing my new design;

FIG. 2 is a perspective view, from an opposite side, showing the inside of the shoe-exhibit;

FIG. 3 is a front view thereof;

FIG. 4 is a top plan view thereof;

FIG. 5 is a bottom plan view thereof; and,

FIG. 6 is a right side view thereof.

The broken lines showing of the shoe in the drawing are for illustrative purposes only and form no part of the claimed design.
